UNITED STATES PATENT OFFICE.

WILLIAM W. KIDENEY, OF CHICAGO, ILLINOIS, AND GUSTAV F. C. BAUER, OF BUFFALO, NEW YORK, ASSIGNORS, BY DIRECT AND MESNE ASSIGNMENTS, TO NATIONAL POLICE SIGNAL COMPANY, OF BUFFALO, NEW YORK, A CORPORATION OF NEW YORK.

POLICE SIGNAL SYSTEM.

Application filed November 3, 1919. Serial No. 335,517.

To all whom it may concern:

Be it known that we, WILLIAM W. KIDENEY and GUSTAV F. C. BAUER, citizens of the United States, and residents of Chicago, in the county of Cook and State of Illinois, and Buffalo, in the county of Erie and State of New York, respectively, have invented new and useful Improvements in Police Signal Systems, of which the following is a specification.

This invention relates to a signal system and more particularly to a signal system for use between a central station and a plurality of sub-stations for police purposes.

The objects of this invention are to provide means for utilizing common battery telephone circuits over which various signals, such as are necessary in a signal system of this character, can be transmitted in a simple and direct manner and so that all electrical energy necessary for the operation of the various signals can be supplied from the central station to the sub-stations over the telephone circuits interconnecting the sub-stations with the central station; also to so organize the system as to permit of eliminating all code signal sending and receiving mechanisms; also to provide special service signals, such as wagon calls and hourly reports, of such a character that the

officer sending the same in from a sub-station will know that the same have been received at the central station; also to provide means for preventing interference or confusion at the central station between signals that may be sent simultaneously from several sub-stations; also to provide visual and audible signals at each sub-station and so arranging the same that the operator at

the central station can at will operate either the visual or audible signals at any one or more sub-stations, as may be desired; also to provide means for supplying the electrical energy necessary for the operation of

said visual and audible signals from the central station to the sub-stations over their respective circuits; also to provide means at the central station to indicate to the operator at the central station that any one has answered said visual or audible signals that may be sent to a sub-station; also to provide means at the central station so that the operator can determine the operative condition of the audible and visual signals at

the various sub-stations; also to provide means at the central station for impressing upon the visual signals at the sub-stations electrical impressions of the same value regardless of the distance between the same and the central station; and to improve the system in other respects as will hereinafter more fully appear.

In the accompanying drawings:

Figure 1 is a diagrammatic view of those portions of our invention embodied in a sub-station together with extensions showing the manner in which an additional audible signal and an additional visual signal may be provided to increase the range of the station. Figure 2 is a similar view showing those parts of our improvements which are embodied in a central station. Figure 3 is a similar view showing the door switch of a sub-station in a position different from that shown in Fig. 1. Figure 4 is a diagrammatic representation of a suitable form of cord circuit and operator's set which may be used in connection with this system.

Similar characters of reference indicate corresponding parts in the several views.

That portion of the mechanism embodying our invention arranged at each of the sub-stations and shown in Fig. 1 is as follows:

A represents the telephone receiver and B the receiver-hook switch having a hook lever b^1 which is adapted to engage the fixed contact b^2 . C represents the transmitter connected by wire 2 with one side of the receiver A and by wire 1 with the contact b^2 .

D represents a door switch which is operated by the opening and closing of the signal box door at the sub-station which switch is so organized that when the door is closed the visual and audible signals at the sub-station are cut into the sub-station circuit and at the same time the telephone apparatus and other parts of the circuit are cut out, but when the door of the signal box is opened the switch D is operated to cut out the visual and audible signal equipment and cuts in the balance of the equipment at the sub-station. This switch comprises an insulating push button d^1 , and two main switch levers d^2 , d^3 . On the outer and inner sides of the contact switch lever d^2 are arranged two contacts

d^5 , d^6 . On the inner and outer sides of the lever contact d^4 are arranged two contacts d^2 , d^3 , respectively.

The contact d^6 is connected by wire 13 with the receiver hook b^1 and the contact d^2 is connected with the opposite side of the transmitter C by wire 3. The main switch levers d^1 , d^4 are connected, respectively, to the wires 4 and 12 of the main circuit connecting the sub-station with the central station.

a is a vibrating buzzer or signal comprising an electro-magnet having one end of its coil a^3 connected by wire 18 with the wire 13, this end of this coil being also connected with a fixed switch contact a^2 which is adapted to be engaged and disengaged by a movable switch contact a^1 formed by the armature of this electro-magnet, this armature switch being connected with the opposite end of the coil of said electro-magnet.

Q is the hourly report switch which in this instance comprises a hand-operated push button q , and two contacts q^1 , q^2 . The contact q^2 is connected by wires 16, 17 with the armature contact q^1 and the corresponding end of its electro-magnet coil a^3 . The companion switch contact q^1 is connected with ground P^4 by wire 15, 14.

S represents the wagon call switch forming part of the means whereby a call for a wagon is sent by an officer from the sub-station to the central station. This switch comprises a push button s , two switch lever contacts s^1 , s^4 , an inner fixed contact s^2 and an outer fixed contact s^3 which is engaged by the lever contact s^4 . The contact s^3 is connected by wire 26 with the wire 14 leading to ground P^4 and the contact s^2 is connected by wire 31 with the wire 17 leading to the coil a^3 and armature contact a^1 of the buzzer a .

T is a wagon call relay which serves to first provide a path for operation of the recording mechanism at the central station over one side of the telephone circuit and ground, also to connect the buzzer a across the telephone circuit and to maintain this connection until the relay is restored to normal by momentarily cutting off the battery from the line at the central station. This relay comprises an electro-magnet having a coil t one end of which is connected by wires 28, 27 with the contact s^4 , while the other end is connected by wire 29 with wire 13 of the main telephone circuit. This relay electro-magnet operates two switches one of which consists of a movable contact t^1 and a fixed contact t^2 while the other consists of a movable contact t^3 and a fixed contact t^4 . The contact t^1 is connected with the wires 28, 27 leading from the coil t to the contact s^4 while its companion contact t^2 , is connected by wires 30, 14 to ground P^4 . The movable contact t^3 is connected by wire

32 to the lever contact s^1 while its companion fixed contact is connected by wire 33 to the wire 3 of the main telephone circuit.

I is the audible signal at the sub-station which in this instance consists of an electro-magnet having a coil i , a diaphragm armature i^1 adapted to be vibrated by an alternating current passing through the coil i , and a horn i^2 for projecting sound waves created by the diaphragm.

J is the visual signal at the sub-station which in this example consists of an incandescent electric lamp.

L is a condenser arranged at the sub-station so as to prevent the battery current from backing through the signal branch of the circuit at the sub-station. R is the signal selecting relay which is arranged at the sub-station and whereby the operator at the central station can operate the visual or audible signals at the sub-station selectively. This relay comprises an electro-magnet having its coil r connected on one side by wire 43 to ground P^5 . This relay controls a break-and-make switch comprising a movable contact r^1 and two fixed contacts r^2 , r^3 . That end of the relay coil r opposite to the grounded end is connected by wires 42 and 41 with the contact d^3 of the door switch D. The movable contact r^1 is also connected with the door switch contact d^3 by wires 40 and 41. The contact r^2 is connected by wire 39 with one end of coil i of the horn electro-magnet and the other fixed contact r^3 is connected by wire 38 to one side of the visual signal lamp J. One side of the condenser L is connected by wires 35 and 34 with the contact d^5 of the door switch D while the other side of this condenser is connected with the other side of the lamp J by wires 36 and 37 and to the other end of the horn coil i by wires 36 and 44.

When it is desired to provide audible and visual signals at a distance from the sub-station which may be operated in unison with those located directly at the sub-station, and thus increase the range of the audible and visual signal mechanism, an extension of the audible and visual signal mechanism may be provided consisting of an extension audible signal I^1 , an extension visual signal J^1 , a relay R^1 and an extension condenser L^1 which may be connected with each other in the same manner as the signals I and J, the relay R and the condenser L and connected with the door switch contacts d^5 and d^3 by wires 41¹ and 35¹.

The instrumentalities of this system arranged at the central station are constructed as follows:

M represents the sub-station line-jack by means of which telephone communication may be established with the sub-station in the usual manner of telephone service. This

jack comprises two line terminal contacts which are adapted to engage with the tip and sleeve of a plug of a connecting cord circuit, as will be hereinafter described, a

5 guide ring m^6 being arranged in front of these two contacts for guiding a plug into engagement with these contacts. The line-jack also includes three auxiliary contacts m^3 , m^4 , m^5 . An insulating block m is interposed between the line contact m^2 and the auxiliary contact m^3 .

10 O is a condenser for the purpose of preventing grounding the hour report circuit through the medium of the cord circuit as 15 will presently appear. This condenser is connected on one side with the contact m^2 by wire 20.

F , F^1 , F^2 , F^3 , represent the switching key by means of which the audible and visual 20 signals at the sub-station are controlled, the two groups of switch members F , F^1 being operated together as one unit while the two groups of switch members F^2 , F^3 , are also operated as one unit, these two units being 25 arranged so that they cannot be operated at the same time. The main switch contacts f^4 and f^1 of the groups F , F^1 are so constructed that when this part of the key is operated they will be automatically restored 30 when the key lever is released. The main switch contacts f^7 , f^{11} of the groups F^2 , F^3 are so constructed that they will be locked in an operating position until manually released by means of the key lever. Group F 35 comprises three contacts f^4 , f^5 , f^6 of which f^4 is the lever switch contact which in the normal or non-operative position engages with the contact f^5 and disengaged from the contact f^6 , and vice-versa. Group F^1 comprises 40 three contacts f^1 , f^2 , f^3 of which f^1 is the lever switch contact which in the normal or non-operative position engages the contact f^2 and is disengaged from the contact f^3 , and vice versa. Group F^2 comprises four 45 contacts f^7 , f^8 , f^9 , f^{10} and an insulating block f interposed between f^7 and f^9 . Group F^3 comprises two contacts f^{11} , f^{12} which in the normal or non-operative position are disengaged while in the operative position they 50 are engaged.

The contact f^2 is connected by the main line circuit wires 6, 9, with the main line jack contact m^1 and is also connected by wires 6, 6¹ with contact f^7 of switch group 55 F^2 . The contact f^5 of group F is connected by main circuit wire 21 with the opposite side of the condenser O . Contact f^{11} of switch F^3 is connected by wires 16² and 16 with contact m^3 of the jack M .

60 V represents a source of supplying alternating electric current one side of which is connected by wire 45 with the contact f^3 while the other side of the same is connected with the contact f^6 by wires 98 and 46 which latter include a buzzer 97. The electric

source V is utilized for supplying energy for a plurality of sub-station circuits in which case the wires 46, 45 would be multiplied accordingly.

65 E is a signal control relay having one end of the coil e of its electromagnet connected to the main line circuit 4 by means of wire 47 while the other side of the same is connected by wire 48 with contact f^9 of switch group F^2 . The electromagnet of relay E controls a plurality of switches one of which comprises a switch lever contact e^4 which is connected with one side of the sub-station line circuit by wire 12, and which in its non-operative position engages a fixed 70 contact e^5 connected by wire 11 with the contact f^4 of switch group F . Another switch which is controlled by the electromagnet of relay E comprises switch lever contact e^1 which is connected to the other side of the 75 sub-station circuit by wire 4 and which in its normal or non-operative position engages fixed contact e^2 connected by wire 5 with contact f^1 of switch group F^1 . e^7 is a movable switch lever contact which is connected with the switch lever contact e^1 by an insulating member e^{10} and which in its normal or non-operative position is engaged with contact e^8 connected by wire 52 with contact 80 f^{12} of the switch group F^3 .

85 N represents a line lamp signal one of which is connected by wires 17 and 18 to ground P and by wire 16¹ and 16 to contact m^3 of line jack M , also wires 16¹ and 16² to contact f^{11} of switch group F^3 .

90 Z represents a similar lamp signal one of which is associated with each sub-station circuit for the purpose of indicating to the operator at the central station when the visual signal at the corresponding sub-station is being operated. To distinguish this lamp signal from the companion lamp signal, it is preferably colored red or otherwise. One side of this lamp Z is connected by wires 53 and 18 to ground P while the 95 other side of the same is connected by wire 50 to fixed contact e^9 of the relay E .

100 K represents the relay used for making hourly reports from the sub-station at the central station, and also for inductance in the battery supply circuit to the sub-station circuit for telephone use. One side of the coil k of the electromagnet of this relay is connected by wire 10 with the contact f^5 of switch group F while the other side of the 105 same is connected by wire 9, to one side of the common battery H , the other side of the latter being connected by wire 19 with ground P^2 . Forming a part of the relay K 110

120 and operated by its electromagnet is a switch comprising a lever contact k^1 which is movable into and out of engagement with the contact k^2 .

125 G represents the line signal control relay which is used for indicating, through the 130

medium of the lamp N, when a telephone call is made from the sub-station to the central station, and also for operating lamp N as a supervisory signal, and also as an inductance in the battery supply to the sub-station for telephone purposes. The coil g of the electro-magnet of the relay G is connected on one side by wire 7 with contact f^8 of switch group F² and on its other side by wire 8 with grounded side of the common battery H. This relay operates two switches one of which comprises a lever contact g^4 which moves out of and into engagement with a fixed contact g^5 which is connected by wire 21 with fixed contact k^2 of relay K. The other switch associated with the relay G comprises lever contact g^1 connected by wire 14 to one side of the common battery H.

W is a recording mechanism for the purpose of receiving and recording at the central station hourly reports and wagon calls sent from the respective sub-stations. One side of the recorder W is connected by common wire 67 to one side of the common battery H.

The recording mechanism indicated by the reference character "W" is so constructed that it includes a plurality of recording members or elements, each of which form part of and is operable by one of the secondary circuits of the system, so that a signal sent in from the substation over any one of these secondary circuits can be recorded by its independent recording device independently of the operation of the recording device forming part of the other secondary circuits of the recorder W at the central station, thereby preventing confusion of the records at the central station, if signals are sent into the central station from more than one substation at a time. A suitable form of recording mechanism for this purpose is shown in Letters Patent of the United States, No. 1,315,201, granted September 9, 1919.

U represents a slow acting cut-off relay which is interposed between the recording mechanism and the hourly report relay K for the purpose of preventing the recorder from repeating when an hourly report is sent in from any sub-station to the central station. The coil u of the electro-magnet of this relay is connected on one side by wire 25 with the non-grounded side of the common battery H, while its opposite side is connected by wires 24 and 22 to contact g^4 of relay G. The relay U is so constructed that the action of its armature is retarded or delayed in its operative movement which can be accomplished in various ways, for instance, as shown in the drawings, Fig. 2, by connecting with the armature contact u^1 of this relay a weighted pendulum u^3 . u^2 is a fixed contact which is connected by wire

66 with one side of the recording circuit corresponding to the respective sub-station circuit, and which is normally engaged by the movable contact u^1 of the cut-off relay U. The movable contact u^1 is connected by wire 22 with contact g^4 of relay G.

V¹ is an interrupter or contact making-and-breaking mechanism which may be of any suitable construction but which for example may be operated by a rotatable cam v under the control of the operator at the central station and adapted to produce intermittent lighting or flashing of the lamp J in the visual signal circuit of the respective sub-station. To accomplish this a switch mechanism is associated with this cam which comprises four contacts v^1 , v^2 , v^4 , v^5 , the contact v^1 being moved into and out of engagement with the contact v^2 by the cam, an insulating connection v^3 being interposed between the contacts v^2 and v^5 , and the contact v^5 being movable into and out of engagement with the contact v^4 . The contact v^1 is connected by wire 49 to contact f^8 of switch group F² and is also connected by wire 51 to contact e^1 of relay E. The contact v^2 is connected by wire 65 to the non-grounded side of the common battery H¹. The contact v^5 is connected by wire 54 with the contact e^6 of relay E.

W¹ is a transformer of special construction having the usual primary winding w the opposite ends of which are connected by wires 62 and 63 to a source of alternating electric current V². The secondary winding w^1 of this transformer is provided with a plurality of taps connected at different points of its winding, so that alternating currents of various voltages may be drawn from the same at the same time to supply energy to the different sub-stations to compensate for the variations in voltage losses due to the unequal lengths of the circuits of the sub-stations. These taps are shown at w^2 , w^3 , w^4 , and in this instance tap w^4 is shown in service and connected by wire 55 to contact e^8 of relay E.

X is an alternating current buzzer preferably of the polarized bell type such as is commonly used in telephone practice. This buzzer in this instance has a movable armature x^1 and an electromagnet, the coil x of which has one side connected by wires 61 and 56 to the common side of the secondary winding w^1 of the transformer W¹, while the other side of the coil w is connected by wires 60 and 59 with the contact v^4 of the circuit interrupter V¹.

Y is a hand operated test switch which is used in conjunction with the buzzer X as a means of testing the operative conditions of any one of the visual signals J of the several substations. This switch comprises a movable contact y^1 provided with a button y and connected by wires 58 and 59 with contact v^4

of the circuit interrupter V^1 and is movable out of and into engagement with contact y^2 which latter is connected by wires 57 and 56 to the common side of the secondary winding

5 w^1 of the transformer W^1 .

As shown in Fig. 4, the cord circuit comprises two connecting plugs 70, 71 which have tips 72, 73 and sleeves 74, 75, respectively. The tips of both plugs are connected 10 together by wire 76, while the sleeves are connected together by wire 77. Included in each cord circuit there is a listening key 78 having movable switch contacts 79, 80, arranged to be engaged with fixed contacts 15 81, 82, the former being connected by wire 84 and 77 to the sleeves of the respective plugs while the latter is connected by wires 83 and 76 to the tips of the two plugs. 85, 86 represent the primary and secondary of 20 the induction coil, respectively, one side of the primary being connected by wire 90 to one side of the operator's transmitter 88, while the other side of the transmitter is connected by wire 91 with the battery 89. 25 The other side of the battery 89 is connected by wire 92 with the opposite side of the primary 85 of the induction coil. One side of the secondary winding 86 is connected by wire 93 with the contact 79 of the listening 30 key 78 while its other side is connected by wire 94 to one side of the operator's receiver 87 and the other side of the receiver being connected by wire 95 to contact spring 80 of the listening key 78. The contacts 79 and 35 80 of the listening key 78 are engaged and disengaged with the contacts 82 and 81, respectively, by a lever operated insulated button or member 96.

The operation of the various functions of 40 this system is as follows:

The parts of the system are shown in Figs. 1 and 2 in their normal position in which no signals or conversations are being carried on over the circuits, but are in readiness for 45 sending in wagon calls, hourly reports or telephone calls from the sub-stations to the central station or to operate the visual or audible signals at the sub-station from the central station and to hold telephone communication between the central station and the substation when such signals at the substation are answered, and also to test the operative condition of the visual signal at the sub-station from the central station.

50 Assuming that the officer at the sub-station wishes to talk to the operator at the central station, the method of procedure is as follows:

The officer opens the door of the signal 55 box at the sub-station which causes the switch button d to be withdrawn from the position shown in Fig. 1 to the position shown in Fig. 3, thereby disengaging contacts d^1 and d^4 from contacts d^3 and d^5 , respectively, and engaging the contacts d^1 and

d^4 with contacts d^2 and d^6 . This change in the signal box switch D cuts out the audible and visual signal equipment I, J , the signal relay R and condenser L , and cuts in the talking circuit, hourly report circuit and wagon call circuit, so that any one of these three circuits can be used as desired. If now the officer wishes to talk, he removes the receiver A from the switch hook B , which causes the sub-station line lamp signal N 70 at the central station to become lighted indicating to the operator that some one at the corresponding sub-station desires to talk. The circuit at this time is from one side of the receiver A , through wire 2, transmitter C , wire 3, switch contacts d^2, d^1 , wire 4, switch contacts e^1, e^2 , wire 5, key contacts f^1, f^2 , wire 6, 6¹ key contacts f^7, f^8 , wire 7, relay coil g , wire 8, battery H , wire 9, relay coil k , wire 10, key contacts f^5, f^4 , wire 11, 80 relay contacts e^5, e^4 , wire 12, switch contacts d^4, d^6 , wire 13, hook switch contacts b^1, b^2 , wire 1 and back to the other side of the receiver A . The closing of this circuit causes electrical energy to flow through relays G and K , causing both of these relays to operate simultaneously. When relay G is energized, movable switch contact g^4 is disengaged from fixed contact g^5 , this occurring at 85 the same instant that movable switch contact k^1 of relay K is entering into engagement with fixed contact k^2 . The action of contact g^4 of relay G therefore serves to break the circuit which is being established by the switch contact k^1 of relay K for a purpose which will presently appear. At 90 the same time movable switch contact g^1 of relay G is moved out of engagement from fixed contact g^2 and into engagement with contact g^3 , thereby establishing the following auxiliary circuit:

Beginning at battery H the current flows over wire 14, contacts g^1, g^3 , wire 15, jack contacts m^4, m^3 , wires 16, 16¹, through line signal N , and wires 17, 18 to ground P , the opposite side of the battery H being grounded by wire 19 to ground P^2 to complete the circuit. This causes the line signal lamp N to become lighted and thereby indicating that some one at the sub-station wishes to talk to the central station. The operator now inserts either plug 70 or 71 of one of the interconnecting cord circuits into the line jack M , thereby causing the tip 72 or 95 73 of either plug used to engage the jack contact m^1 and the corresponding sleeve 74 or 75 to engage the contact spring m^2 , and also disengaging contact m^3 from contact m^4 and engaging contact m^3 with contact m^5 . This change in the switch contacts m^3, m^4, m^5 extinguishes the lamp N by opening the circuit across contacts m^3, m^4 . At 100 the same time the operator closes the operator's talking circuit across the cord circuit by means of the listening key button 96. 105

A talking circuit is now established between the operator's telephone set and the sub-station telephone set as follows:

Beginning at one side of the secondary winding 86 of the operator's induction coil and extending over wire 93, contacts 79, 82, wire 83, 76, plug tip 72, jack contact m^1 , wire 19, then over line 6 over this circuit to the sub-station previously described and back over wire 11, through key contacts, f^4 , f^5 , then over wire 21, condenser O, wire 20, jack contact m^2 , plug sleeve 74, wires 77, 84, contacts 81, 80, wire 95, through operator's receiver 89, wire 94, to the opposite side of the secondary winding 86 of the operator's induction coil. The primary circuit of the operator's telephone set is as follows:

From side of the battery 89 the current flows over wire 92, through the primary winding 85 of the operator's induction coil, over wire 90, through transmitter 88, and over wire 91 to the opposite side of the battery 89. The sub-station talking set is supplied with battery current at this time through the windings of the relays G and K. Conversation may now be carried on between the sub-station and the central station and when completed the person at the sub-station replaces the receiver A on the switch hook B, thereby disengaging switch contacts b^1 , b^2 of said switch hook, thereby opening the sub-station switch at this point, and causing relays G and K to be restored to normal. When this occurs, the relay contact g^1 is disengaged from contact g^3 and engaged with contact g^2 , thereby establishing an auxiliary circuit as follows: From side of battery H over wire 14, contacts g^1 , g^2 , wire 22, contacts m^5 , m^3 , wires 16, 16 ^{1} , through lamp N, over wires 17, 18 to ground and back to battery over wire 19, thereby causing lamp N to be again lighted and indicating to the operator that the cord connections may be removed.

When the relays G and K are restored to normal in the manner above described, contacts g^4 , g^5 , are again engaged and contacts k^1 , k^2 are again disengaged, thereby restoring this part of the circuit to its normal condition. From the above description it will be evident that the line lamp signal N is used as a supervisory signal in place of the common method of including a supervisory signal in the cord circuit.

When the switch D is in the position indicated in Fig. 3, which is the position it assumes upon opening the signal box door, an hourly report may be sent from the sub-station to the central station by depressing the button Q of the hourly report switch Q. When this is done contacts g^1 , g^2 are engaged, thereby establishing the following circuit: From ground P ^{4} over wires 14, 15, contacts g^1 , g^2 , wires 16, 17, through the coil a^3 of the buzzer a, wires 18, 13, switch

contacts d^8 , d^4 , wire 12, contacts e^4 , e^5 , wire 11, key contacts f^4 , f^5 , wire 10, through relay coil k, wire 9, to one side of battery H and from the opposite side of this battery over wire 19 to ground.

The buzzer a has its coil a^3 permanently connected between the wires 17, 18, and has its contacts a^1 , a^2 , so arranged that while in operation they cause said coil to be shunted into and out of the circuit and thus cause the buzzer to vibrate and operate as an audible signal which indicates the operative condition of the hourly report circuit, this being accomplished without opening this circuit which otherwise would be the case if an ordinary buzzer were employed. When this circuit is established relay K becomes operative causing contacts k^1 , k^2 to engage and closing two auxiliary circuits as follows: First, the recorder circuit, from ground P ^{2} over wires 19, 20, contacts k^1 , k^2 , wire 21, contacts g^3 , g^4 , wire 22, contacts u^1 , u^2 , wire 66, through one of the individual recording members of the recorder W, wire 67, through battery H, to group P ^{2} , causing a record to be made by the recording mechanism W. The other, the cut-off circuit flows over the first part of the above described recorder circuit up to and including wire 22, from whence it extends over wire 24 through relay coil U, over wires 25, 14, through battery H, wire 19, to ground P ^{2} , causing relay U to operate. The operation of relay V disengages contact u^1 from u^2 , thereby opening the circuit to the recording mechanism. Inasmuch as relay U is of the retarding or slow-acting type, a sufficient current impulse has been allowed to pass over the recording circuit to permit the recording mechanism to operate but once, repeated operation of the recording mechanism being thereby prevented if the button Q is maintained in an operative position. It is therefore possible for the officer in making an hourly report to maintain the button Q in an operative position sufficiently long to satisfy himself by means of the buzzer a that the recording circuit is in an operative condition without thereby causing the recording mechanism to repeat.

When button Q is released and contacts g^1 , g^2 are thereby disengaged, the recording circuit is opened at this point causing relay K to be again restored to its normal condition. This causes contacts k^1 , k^2 to be disengaged, thereby opening the circuit through the cut-off relay U, causing the latter to also be restored to its normal position when contacts u^1 , u^2 are again engaged, thereby placing the entire recording circuit in a position in which the same cycle of operations can be repeated.

When the switch D is in the position indicated in Fig. 3, which is the position it assumes upon opening the signal box door,

a wagon call may be sent from the sub-station to the central station by depressing the bottom s of the wagon call switch S.

When this button s is depressed it causes

5 contact springs s^1 and s^2 to disengage and contact springs s^3 and s^4 to engage. When contact springs s^3 and s^4 are engaged a circuit is formed as follows:

From ground P^4 over wires 14, 26, through

10 spring contacts s^3 , s^4 , wires 27, 28, through winding t of relay T, over wires 29 and 13 and then following the same course as the circuit for hourly report from this point on.

In fact, this part of the wagon call circuit

15 performs the function of the previously described hourly report circuit, with the exception that in this instance the circuit is closed at the sub-station through the coil t of relay T in place of going through the

20 winding a^3 of the buzzer a . When relay T is energized, contacts t^1 and t^2 of said relay T are engaged, thereby providing a shunt circuit around the switch contacts s^3 and s^4 as follows:

25 From ground P^4 over wires 14 and 30, contacts t^2 and t^1 of relay T, wire 28 to winding t and then following the same path as previously described with reference to the recorder part of wagon call circuit. When

30 the button s is released, thereby opening the original circuit at contacts s^3 and s^4 , relay T will still remain energized by reason of the shunt circuit above described. When button s is restored to normal, the contacts

35 s^1 and s^2 again engage, thereby closing the circuit across the main lines 3, 13 through the buzzer a as follows:

From wires 13, 18, through coil winding a^3 of short circuiting buzzer a , over wires 17

40 and 31, contacts s^2 and s^1 , over wire 32 to contacts t^3 and t^4 of relay T, and over wire 33 to wire 3. This circuit is then completed through the central office equipment in the same manner as a regular telephone call

45 previously described. When this circuit is closed as above described the buzzer a will operate and the sound of the buzzer will be audible to the party making the call. At the same time a telephone call will be sig-

50 nalled on the line signal lamp N and when the operator answers said call in the usual manner, as previously described, he will hear the buzzer or rather the effect produced by the cutting in and out of the winding of the

55 buzzer, and by reason of this sound he will know the nature of the call without having to actually hold conversation with the man at the sub-station. When the operator has ascertained the nature of the call, he opens

60 the main line circuit by operating signal key groups F, F¹, thereby cutting off the battery supply at this point by the disengaging of the contacts f^4 , f^5 of the above-mentioned key. This causes relay 2 to be restored to its

65 normal non-operative position. When relay T is restored to normal position the circuit through buzzer a is opened at contacts t^3 and t^4 which are now disengaged, the buzzer will cease to operate. When the buzzer stops, the man at the sub-station knows that his 70 call has been received at the central station. As previously stated, when relay T is energized it forms a part of the recording circuit and therefore a record is made on the recording mechanism. 75

75 It will be noted that when making a wagon call the buzzer a is connected across the circuit 3, 13, at the sub-station while when making an hourly report the buzzer a is connected from one side of this circuit 80 between wire 13 and ground at the sub-station.

85 In the previously described operations, originated at the sub-station all of the functions that can be performed at the sub-station have been described. In each of these operations the switch D is in the position as shown in Fig. 3. The switch D is operated by the door of the signal box and therefore the switch automatically assumes the proper position for the service to be performed. When the signal box is closed the switch D is in the position as shown in Fig. 1, and is then in a position so that either the audible or visual signals located at the sub-station can be operated from the 90 central station. 95

95 When the audible signal at the sub-station is to be sounded, it is only necessary to depress signal key groups F, F¹. This causes contact f^1 to be disengaged from contact f^2 and engage contact f^3 , and contact f^4 to be disengaged from contact f^5 and to engage with contact f^6 . When the circuit is broken between contacts f^1 and f^2 , and between contacts f^4 and f^5 , all parts of the central station equipment extending from wires 6 and 21 which terminate on contacts f^2 and f^5 , are cut off from the line circuit so that the 100 signal current cannot back up through any part of said central station equipment. 105

105 We have now established an electrical circuit from the alternating current source V at the central station over the sub-station line circuit through the audible signal I 110 located at the sub-station as follows:

110 From one side of the V over wire 45, contacts f^3 , f^1 , wire 5, contacts e^2 , e^1 , wire 4, contacts d^1 , d^2 , wires 41, 40, contacts r^1 , r^2 , 115 wire 39, through coil i of audible signal I, over wires 44, 36 through condenser L, wires 35, 34, contacts d^5 , d^4 , wire 12, contacts e^4 , e^5 , wire 11, contacts f^4 , f^5 , wire 46, through buzzer 97, wire 98 to the other side of the 120 electric source V. The audible signal will now operate and continue to do so until the switch groups F, F¹ are restored to their normal position, or until an officer answers the signal at the sub-station. At the same 125 time that the audible signal I at the sub- 130

station is in operation, the buzzer 97, which is included in this circuit, also operates, thus indicating the operative condition of this circuit. The instant the officer opens the 5 door of the sub-station signal box to answer the call, the door switch D automatically assumes the position shown in Fig. 3, thereby opening the audible signal circuit by disengaging contacts d^1 , d^3 and d^4 , d^5 which 10 form a part of this circuit. The audible signal I at the sub-station now ceases to operate and for the same reason the buzzer 97 at the central station ceases to operate, thereby indicating to the operator that the officer is 15 answering the call at the sub-station. The operator now restores the switch groups F, F^1 to their normal condition, thereby re-establishing the line circuit to its normal condition and permitting telephone communication 20 to be carried on between the central station and the sub-station, as previously described.

If it is desired to set in operation the 25 visual signal J at the sub-station, the operator at the central-station sets the signal key of the switch groups F^2 , F^3 to the operating position which causes the contacts f^7 , f^8 to be disengaged and at the same time causes contacts f^9 , f^{10} to be engaged and 30 also contacts f^{11} , f^{12} to engage. When contacts f^7 , f^8 are disengaged relay G is cut off from the line circuit at this point for a reason which will presently appear. When the operator is about to cause the visual signal 35 I to operate, he also causes the cam v of the circuit interrupter to rotate either manually or otherwise, so that the circuit interruptions occur at this point by the engagement and disengagement of the contacts v^1 , v^2 and v^4 , v^5 , the rate of such interruptions being preferably at the rate of approximately sixty times per minute. This rate of interruption produces a flash 40 visual signal which is readily recognized and not liable to be confused with other signals. The circuit through the visual signal is now established during the periods when contacts v^1 , v^2 , and v^4 , v^5 are engaged and the circuit is opened through the visual signal when contacts v^1 , v^2 and v^4 , v^5 are disengaged, without any further manipulation of the signal key controlling the 45 switch groups F^2 , F^3 . We will first trace the battery circuit through the relays E and R controlling the circuit through the visual signal J as follows: from the battery H^1 , wire 65, contacts v^2 , v^1 , contacts f^9 , f^{10} , wire 48, coil e of relay E, wires 47, 4, switch contacts d^1 , d^3 , of door switch D, wires 35¹, 42¹, 50 through coil r of relay R, wire 43 to ground P^5 , and back to the opposite side of battery H over ground P^1 and wire 64. This now causes relays E and R to operate. On relay E contact e^4 is disengaged from contact 55 e^5 and engaged with contact e^6 , contact

e^1 is disengaged from contact e^2 and engaged with contact e^3 , and contact e^7 is disengaged from contact e^8 and engaged with contact e^9 . At the same time on relay R, contact r^1 is disengaged from contact r^2 and engaged with contact r . The circuit through the visual signal J is now established as follows: from one side of the secondary winding w^1 of the transformer W^1 , the current passes over wires 56, 57, through 70 switch contacts y^1 , y^2 , over wires 58, 59, contacts v^4 , v^5 , wire 54, contacts e^6 , e^4 , wire 12, door switch contacts d^4 , d^5 , wires 34, 35, condenser L, wires 36, 37, through signal lamp J, wire 38, contacts r^3 , r^1 , wires 40, 80 41, contacts d^2 , d^1 , wire 4, contacts e^1 , e^3 , wire 55, to terminal w^4 on the other side of the secondary winding w^1 of the transformer W^1 . At this time it is assumed that electric current is flowing from the source 85 V^3 over wire 62, through primary winding w of the transformer W^1 , wire 63 back to the opposite side of this electric source.

The signal lamp J will now operate and will continue to operate until the cam v 90 causes the contacts v^1 , v^2 and v^4 , v^5 to disengage or until the officer answers at the sub-station by the opening of the signal box door which causes switch D to assume the 95 position shown in Fig. 3, whereby the circuit is opened at this point. At the same time that the signal circuit is established, a secondary circuit is established in the central station as follows:

From one side of the battery H^1 over wire 100 65, contacts v^2 , v^1 , wire 51, contacts e^7 , e^9 , wire 50, through lamp Z, wires 53, 18 to ground P, and back to battery H^1 , over ground P^1 and wire 64. This causes lamp Z to operate, this lamp operating in unison with the sub-station signal lamp J, indicating to the operator at the central station that the battery control circuit through relays E and R is in an operative condition and also serves as a reminder to the operator that the signal 110 circuit on this particular sub-station line is being operated. If for any reason the door of the sub-station signal box is not properly closed which would cause the door switch to assume the position shown in Fig. 3, then the battery circuit through the relays E and R could not be established because said circuit would be open between contacts d^3 , and d^1 , and this would prevent the signal lamp Z from lighting and the lamp N would be lighted instead over the following circuit: from one side of battery H^1 , over wire to contacts v^2 , v^1 , wire 51, contacts e^7 , e^8 , wire 52, contacts f^{12} , f^{11} , wires 16², 16¹, 115 through lamp N, wires 17, 18 to ground P and back to battery H^1 , as previously described. This last-mentioned condition of the lighting of lamp N is intentionally used as an incoming signal when the officer opens the sub-station signal box door to answer 120 125 130

- the call of the visual signal J which has been made from the central station. When said call is answered by the officer and the operator at the central station has been 5 made aware of the officer's presence at the sub-station by the lighting of the lamp, the operator immediately restores the switch groups F², F³ to their normal position indicated in Fig. 1, and then when the officer 10 at the sub-station removes the receiver A from the switch hook B, the signal lamp N, which previously was flashing, is now constantly lit, as in an incoming telephone call and said call is answered, as previously 15 described. The reason for flashing the lamp N under these conditions is to indicate to the operator the necessity of restoring the switch groups F², F³ to normal, so that battery current can be supplied from the 20 battery H over the sub-station circuit for talking purposes, this act again cutting into the line circuit of the relay G. The relay G is purposely cut out of the circuit during the operation of the visual signal J for the 25 following reason: If relay G were left in circuit a momentary auxiliary circuit would be established every time that cam v caused contacts v¹, v² to engage as follows: from battery H¹, over wire 65, contacts v², v¹, wire 49, contacts f⁹, f¹⁰, wire 30 48, coil e of relay E, wire 47, contacts e¹, e², wire 5, contacts f¹, f², wires 6, 7, through coil g of relay G, wires 8, 19, to ground P², and back to opposite side of battery H¹ 35 over ground P¹ and wire 64. Before relay E could operate a sufficient current impulse would flow through relay G over the circuit above described to cause the same to operate momentarily at each impulse of this 40 kind and thereby cause a disagreeable flashing of the lamp N. To prevent this, wire 7 is separated from wire 6 by means of contacts f⁷ and f⁸ in switch group F² when the signal key lever is placed in position for 45 operating the visual signal J.
- Contacts v⁴, v⁵ are included in the transformer circuit and are operated by the cam v for the purpose of interrupting the alternating current used for energizing the 50 visual signal lamp so as to prevent the deterioration or unnecessary burning of the contacts e¹, e³, e⁴, e⁶, of the relay E which would be the case if this part of the secondary circuit of the transformer W¹ were 55 run direct to said relay contact e³.
- If it is desired to test the operative condition of the visual signal J at the sub-station from the central station, this test can be made on each sub-station line individually when the signal circuit for operating 60 said visual signal J is placed in the operative position by means of the signal key of switch group F², F³, in the manner previously described for the operation of the visual signal J, in the following manner:

Button y of test switch Y is depressed so as to disengage contacts y¹, y². If the visual signal lamp J is operating the buzzer X will now operate. If, however, the signal lamp J, or the visual signal circuit is not in an operative condition, the buzzer X will not operate. The reason for this is that normally, contacts y¹, y² are engaged and with wires 57 and 58 provide a low resistance shunt circuit around the buzzer X. When, however, contacts y¹, y² are disengaged by the operation of the button y the current from the secondary winding w' of the transformer W¹ is compelled to pass by wires 60 and 61 through the coil x of the buzzer X over the visual signal circuit as previously described, thereby providing a means of readily determining the operative and non-operative condition of the sub-station visual signals.

If it is desired to simultaneously operate an extension visual and audible signals J¹ I¹, in connection with the signals J and I at the sub-station, this can be done in the manner indicated in Fig. 1, and thus increase the range of the signalling capacity accordingly.

We claim as our invention:

1. A signal system for use between a central station and a sub-station, comprising a telephone circuit between said stations, an auxiliary circuit combined with said telephone circuit having means for making records at the central station from the sub-station, said auxiliary circuit including means for indicating the operative condition of said auxiliary circuit, a special service circuit combined with said telephone and auxiliary circuits including said means for making a record over said auxiliary circuit and at the same time indicating at the central station the nature of said special service, said telephone circuit including at the sub-station said indicating means which are used in the auxiliary circuit when a record is being made at the central station from the sub-station, and said indicating means being also used across the telephone circuit when said special service circuit is in operation.

2. A signal system for use between a central station and a sub-station, comprising a telephone circuit between said stations, an auxiliary circuit combined with said telephone circuit having means for making records at the central station from the sub-station, said auxiliary circuit including means for indicating the operative condition of said auxiliary circuit, a special service circuit combined with said telephone and auxiliary circuits including said means for making a record over said auxiliary circuit and at the same time indicating at the central station the nature of said special service, said telephone circuit including at the sub-

- station said indicating means which are used in the auxiliary circuit when a record is being made at the central station from the sub-station, and said indicating means being also used across the telephone circuit when said special service circuit is in operation, and said special service circuit including a relay located in said auxiliary circuit and so arranged as to maintain said indicating means across the telephone circuit when said special service circuit is in operation.
3. A signal system for use between a central station and a sub-station, comprising a telephone circuit between said stations, an auxiliary circuit combined with said telephone circuit having means for making records at the central station from said sub-station, said auxiliary circuit including means for indicating the operative condition of said auxiliary circuit, a special service circuit combined with said telephone and auxiliary circuits including said means for making a record over said auxiliary circuit and at the same time indicating at the central station the nature of said special service, said telephone circuit including at the sub-station said indicating means which are used in the auxiliary circuit when a record is being made at the central station from the sub-station, and said indicating means being also used across the telephone circuit when said special service circuit is in operation, and said special service circuit including a relay located in said auxiliary circuit and so arranged as to maintain said indicating means across the telephone circuit when said special service circuit is in operation; and said special service circuit including means at the central station for restoring said special service circuit at the sub-station to its normal non-operative condition.
4. A signal system for use between a central station and a sub-station, comprising a telephone circuit between said stations, an auxiliary circuit combined with said telephone circuit having means for making records at the central station from said sub-station, said auxiliary circuit including means for indicating the operative condition of said auxiliary circuit, a special service circuit combined with said telephone and auxiliary circuits including said means for making a record over said auxiliary circuit and at the same time indicating at the central station the nature of said special service, said telephone circuit including at the sub-station said indicating means which are used in the auxiliary circuit when a record is being made at the central station from the sub-station, and said indicating means being also used across the telephone circuit when said special service circuit is in operation, and said special service circuit including at the sub-stations in said auxiliary circuit a relay and a manually operable switch, said switch arranged to place said relay in an operative condition, said relay being arranged so that its operative condition is automatically maintained when said switch is released, said relay being also provided with means for connecting said indicating means across the telephone circuit while the relay is in an operative position.
5. A signal system for use between a central station and a sub-station, comprising a telephone circuit between said stations, an auxiliary circuit combined with said telephone circuit having means for making records at the central station from said sub-station, said auxiliary circuit including means for indicating the operative condition of said auxiliary circuit, a special service circuit combined with said telephone and auxiliary circuits including said means for making a record over said auxiliary circuit and at the same time indicating at the central station the nature of said special service, said telephone circuit including at the sub-station said indicating means which are used in the auxiliary circuit when a record is being made at the central station from the sub-station and said indicating means being also used across the telephone circuit when said special service circuit is in operation and said special service circuit including at the sub-stations in said auxiliary circuit a relay and a manually operable switch, said switch arranged to place said relay in an operative condition, said relay being arranged so that its operative condition is automatically maintained when said switch is released, said relay being also provided with means for connecting said indicating means across the telephone circuit while the relay is in an operative condition and said special service circuit including means at the central station for restoring said special service circuit at the sub-station to its normal non-operative condition.
6. A signal system for use between a central station and a sub-station, comprising a telephone circuit between said stations, an auxiliary circuit combined with said telephone circuit having means for making records at the central station from said sub-station, said auxiliary circuit including means for indicating the operative condition of said auxiliary circuit, a special service circuit combined with said telephone and auxiliary circuits including said means for making a record over said auxiliary circuit and at the same time indicating at the central station the nature of said special service, said telephone circuit including at the sub-station said indicating means which are used in the auxiliary circuit when a record is being made at the central station from the sub-station, and said indicating means being also used across the telephone circuit when said special service circuit is in operation, and said special service circuit including at the sub-stations in said auxiliary circuit a

- cuit when said special service circuit is in operation and said special service circuit including at the sub-stations in said auxiliary circuit a relay and a manually operable switch, 5 said switch arranged to place said relay in an operative condition, said relay being arranged to that its operative condition is automatically maintained when said switch is released, said relay being also provided 10 with means for connecting said indicating means across the telephone circuit while the relay is in an operative condition, said switch so arranged that when in an operative condition said indicating means are disconnected 15 from the telephone circuit.
7. A signal system for use between a central station and a sub-station, comprising a telephone circuit between said stations, an auxiliary circuit combined with said telephone circuit having means for making records at the central station from said sub-station, said auxiliary circuit including means for indicating the operative condition of said auxiliary circuit, a special service 20 circuit combined with said telephone and auxiliary circuits including said means for making a record over said auxiliary circuit and at the same time indicating at the central station the nature of said special service, said telephone circuit including at the sub-station said indicating means which are used in the auxiliary circuit when a record is being made at the central station from the sub-station, and said indicating means being also used across the telephone circuit when said special service circuit is in operation and said special service circuit including at the sub-stations in said auxiliary circuit a relay and a manually operable 25 switch, said switch arranged to place said relay in an operative condition, said relay being arranged so that its operative condition is automatically maintained when said switch is released, said relay being also provided with means for connecting said indicating means across the telephone circuit while the relay is in an operative condition, said switch so arranged that when in an operative condition said indicating means are disconnected from the telephone circuit and said special service circuit including means at the central station for restoring said special service circuit at the sub-station to its normal non-operative condition. 30
8. A signal system for use between a central station and a sub-station, comprising a telephone circuit between said stations, an auxiliary circuit combined with said telephone circuit having means for making records at the central station from said sub-station, said auxiliary circuit including means for indicating the operative condition of said auxiliary circuit, a special service circuit combined with said telephone and auxiliary circuits including said means for making a record over said auxiliary circuit and at the same time indicating at the central station the nature of said special service, said telephone circuit including at the sub-station said indicating means which are used in the auxiliary circuit when a record is being made at the central station from the sub-station, and said indicating means being also used across the telephone circuit when said special service circuit is in operation, said indicating means being arranged to give a vibratory signal without opening the telephone circuit while in operation. 35
9. A signal system between a central station and a plurality of sub-stations arranged at different distances from said central station, comprising a plurality of individual circuits each connecting said central station with one of said sub-stations, a transformer arranged at the central station and having its primary winding connected with a source of electrical energy while its secondary winding is permanently connected at different points with said individual circuits according to the length of the same for producing electric impressions of the same value at the several sub-stations regardless of the distance between the same and the central station, and visual signals arranged in said circuits at the sub-stations. 40
10. A signal system between a central station and a plurality of sub-stations arranged at different distances from said central station, comprising a plurality of individual circuits each connecting said central station with one of said sub-stations, a transformer arranged at the central station and having its primary winding connected with a source of electrical energy while its secondary winding is connected at different points with said individual circuits according to the length of the same for producing electric impressions of the same value at the several sub-stations regardless of the distance between the same and the central station, visual signals arranged in said circuits at the sub-stations, and means at each sub-station for cutting off the electric current at the central station from the circuit of the respective sub-station. 45
11. A signal system between a central station and a plurality of sub-stations arranged at different distances from the central station, a plurality of telephone circuits each connecting said central station with one of said sub-stations, a visual signal arranged in each of said circuits at the respective sub-station, a transformer arranged at the central station and having its primary winding connected with a source of electric energy while different points of its secondary winding are connected with said circuits according to the distance of the respective sub-stations from the central station for producing 50

- electrical impressions of the same value on the visual signals at the several sub-stations, means for impressing the electrical energy from said transformer on the circuits of any one or more of said sub-stations at will, and means at each sub-station for cutting off the electrical current at the central station from the circuit of the respective sub-station and for preventing said current from being impressed on said circuit while said substation is in use, and means at the central station operated from the sub-stations for indicating that the signal has been received at the particular sub-station.
12. A signal system between a central station and a plurality of sub-stations arranged at different distances from the central station, a plurality of telephone circuits each connecting said central station with one of said sub-stations, a visual signal arranged in each of said circuits at the respective sub-station, a transformer arranged at the central station and having its primary winding connected with a source of electric energy while different points of its secondary winding are connected with said circuits according to the distance of the respective sub-stations from the central station for producing electrical impressions of the same value on the visual signals at the several sub-stations, means for impressing the electrical energy from said transformer on the circuits of any one or more of said sub-stations at will, means at each sub-station for cutting off the electrical current at the central station from the circuit of the respective sub-station and for preventing said current from being impressed on said circuit while said sub-station is in use, means at the central station operated from the sub-stations for indicating that the signal has been received at the particular sub-stations, and means at the central station for individually testing at will the operative condition of the visual signals located at said sub-stations while one of said signal circuits is set for operation.
13. A signal system between a central station and a plurality of sub-stations arranged at different distances from said central station, a plurality of telephone circuits each connecting said central station with one of said sub-stations, means associated with said telephone circuits for producing records from said sub-stations at the central station and so organized that the telephone circuit and recording means are operated independently of each other, a special circuit at each sub-station associated with its respective telephone circuit and having a manually operable switch, a vibrating indicator associated with each of said telephone circuits and special circuit which when once set in operation at the sub-station will continue to operate until restored for informing the officer at the sub-station that the circuit is in an operative condition and also for informing the officer at the central station as to the nature of said special service desired at the sub-station, means at the central station for restoring said special circuit to its normal non-operative condition, a visual signal and an audible signal arranged in each of said circuits at the respective sub-stations, means at the central station for operating said signals selectively on any one or more of said sub-stations, a transformer arranged at the central station for supplying

the energy for operating the visual signals and having its primary winding connected with a source of electric energy while different points of its secondary winding are connected with said circuits according to the distance of the respective sub-stations, from the central station for producing electrical impressions of the same value on the visual signals at the several sub-stations, 5 means at each sub-station for cutting off the electrical current at the central station from the circuit of the respective sub-station and for preventing said current from being impressed on said circuit while said sub-station 10 is in use, means at the central station for 15 individually testing at will the operative condition of the visual signals located at said sub-stations while one of said visual signals is set for operation, means for supplying electric current for operating said audible 20 signals of the several sub-stations over their respective telephone circuits, means at the central station for indicating the operative condition of said audible signal circuits, and means at the central station operated from 25 the sub-stations for indicating that a signal has been received at the particular sub-stations.

WILLIAM W. KIDENEY.
